(57) **CLAIM**

The ornamental design for an aerator for a composting bin, as shown and described.

DESCRIPTION

FIG. 1 is a perspective view of an aerator for a composting bin according to a preferred embodiment of the present invention;

FIG. 2 is a bottom view thereof;

FIG. 3 is a front view thereof;

FIG. 4 is a side view thereof;

FIG. 5 is a top view thereof;

FIG. 6 is a perspective view of an aerator for a composting bin according to an alternate embodiment of the present invention;

FIG. 7 is a bottom view of the alternate embodiment shown in FIG. 6;

FIG. 8 is a front view of the alternate embodiment shown in FIG. 6;

FIG. 9 is a side view of the alternate embodiment shown in FIG. 6;

FIG. 10 is a top view of the alternate embodiment shown in FIG. 6;

FIG. 11 is a perspective view of an aerator for a composting bin according to another alternative embodiment of the present invention;

FIG. 12 is a bottom view of the alternate embodiment shown in FIG. 11;

FIG. 13 is a front view of the alternate embodiment shown in FIG. 11;

FIG. 14 is a side view of the alternate embodiment shown in FIG. 11; and,

FIG. 15 is a top view of the alternate embodiment shown in FIG. 11.
